OVERSHOE

Duncan E. Slade, Naugatuck, Conn., assignor to Uniroyal,
Inc., a corporation of New Jersey

Filed Nov. 18, 1966, Ser. No. 4,731

Term of patent 14 years

(Cl. D2—271)

FIG. 1

FIG. 2

FIG. 3

FIG. 4

FIG. 5

FIG. 1 is a top plan view of an overshoe embodying my new design;

FIG. 2 is a bottom plan view of the sole portion of the overshoe;

FIG. 3 is a side elevational view of the overshoe;

FIG. 4 is a side elevational view taken from the side opposite to that shown in FIG. 3; and

FIG. 5 is a rear elevational view of the overshoe.

The essential features of my design reside in the portion thereof shown in FIG. 2.

I claim:

The ornamental design for an overshoe, substantially as shown and described.
